DISPLAY RACK FOR MERCHANDISE

Robert C. Barry, Newtown Square, Pa., assignor to
Cooper Industries, Inc., Houston, Tex.

Filed Oct. 23, 1973, Ser. No. 408,613

Term of patent 14 years

Int. Cl. D20—02

U.S. Cl. D6—114

Fig. 1

Fig. 2

Fig. 6

*Fig. 3**Fig. 4**Fig. 5*

FIG. 1 is a perspective view of a display rack for merchandise showing my new design;

FIG. 2 is a side elevational view thereof, the opposite side being identical;

FIG. 3 is a top plan view thereof;

FIG. 4 is a front elevational view thereof;

FIG. 5 is a bottom plan view thereof;

FIG. 6 is a fragmented front elevational view of a modified embodiment of the display rack for merchandise shown in FIG. 1, the differences residing in the equi-spaced divider panels and said embodiment being broken away to indicate indeterminate length.

I claim:

The ornamental design for a display rack for merchandise, as shown and described.
